UNITED STATES PATENT OFFICE.

WILLIAM S. HARLEY, OF MILWAUKEE, WISCONSIN, ASSIGNOR TO HARLEY-DAVIDSON MOTOR CO., OF MILWAUKEE, WISCONSIN, A CORPORATION OF WISCONSIN.

DESIGN FOR A MOTORCYCLE-SIDE-CAR BODY.

57,335.

Specification for Design.

Patented Mar. 15, 1921.

Application filed July 9, 1920. Serial No. 395,159. Term of patent 7 years.

To all whom it may concern:

Be it known that I, WILLIAM S. HARLEY, a citizen of the United States, residing at Milwaukee, in the county of Milwaukee and State of Wisconsin, have invented a new, original, and ornamental Design for a Motorcycle-Side-Car Body, of which the following is a specification, reference being had to the accompanying drawing, forming a part thereof.

Figure 1 is a top plan of the side car body, embodying the new design, and

Fig. 2 is a side elevation thereof.

What is claimed is:

The ornamental design for a motorcycle side car body as shown.

In witness whereof I have hereunto subscribed my name.

WILLIAM S. HARLEY.
